UNITED STATES PATENT OFFICE.

DUNCAN J. FEELY, OF SAN DIEGO, CALIFORNIA.

IRONING DEVICE.

1,079,168.

Specification of Letters Patent.

Patented Nov. 18, 1913.

Application filed October 25, 1912. Serial No. 727,808.

To all whom it may concern:

Be it known that I, DUNCAN J. FEELY, a citizen of the United States, residing at San Diego, in the county of San Diego and State 5 of California, have invented certain new and useful Improvements in Ironing Devices; and I do declare the following to be a full, clear, and exact description of the invention, such as will enable others skilled 10 in the art to which it appertains to make and use the same.

This invention relates to improvements in ironing devices.

One object of the invention is to provide 15 an ironing device having an improved means for exerting a yielding pressure on the iron without interfering with the free movement thereof in any direction and having means whereby the pressure on the iron 20 may be adjusted.

Another object is to provide a device of 25 this character which will be simple, strong, durable and inexpensive in construction, efficient and reliable in operation and which 30 may be attached to the ceiling of any room and when not in use may be folded back to an out of the way position.

With these and other objects in view, the 35 invention consists of certain novel features of construction and the combination and arrangement of parts as will be more fully described and claimed.

In the accompanying drawings; Figure 1 is a side view of my improved ironing device 40 showing the parts in operative position in full lines and in inoperative position in dotted lines; Fig. 2 is an end elevation of the same; Fig. 3 is a perspective view of the iron; Fig. 4 is an enlarged vertical section 45 of the lower end of the iron engaging member of the pressure bar of the device.

My improved ironing device comprises a spring 1 which may be of any suitable construction but which is here shown and is 50 preferably in the form of a double bowed spring, the upper member 2 of which is secured by screws or other suitable fastening devices to a ceiling or any overhead support. To the lower member 3 of the spring 55 midway between its ends is secured a pressure bar attaching plate 4. The plate 4 is secured at its ends to the member 3 by bolts or rivets and is spaced from said member as shown. In the center of the plate 4 is 60 formed a circular aperture 5 the purpose of which will hereinafter appear.

Secured to the spring 1 is a pressure bar 6 by means of which the yielding pressure of the spring 1 is applied to the iron. The upper end of the pressure bar 6 is attached 60 to the spring 1 by means of a coupling member 7 comprising a flat plate which is engaged with a notch 8 in the upper end of the pressure bar and is securely bolted to said end as shown. On the plate 7 is an upwardly projecting shank 9 having on its upper end a head 10. The shank 9 is engaged with the aperture 5 in the plate 4 while the head 10 is disposed between the plate and lower member 3 of the spring, 70 said head bearing against the lower member of the spring as shown. The aperture 5 in the plate 4 is of sufficient size to permit the pressure bar 6 to swing freely in all directions, but is not large enough to permit the 75 head 10 to pass therethrough. It will be understood that the shank 9 is engaged with the aperture 5 in the plate 4 before the head 10 is formed on the shank and that after the shank has been engaged with the plate 4 80 and headed said plate is bolted or otherwise fastened to the lower member of the spring.

In the lower end of the pressure bar 6 is a longitudinal slot 11. Adjustably secured to the slotted lower end of the bar 6 is an iron 85 engaging member 12 having on its upper end a flat plate 13 with which are engaged attaching bolts 14 which are also slidably engaged with the slot 11 and have on their threaded ends clamping nuts which are 90 shown screwed up into engagement with the outer face of the plate 13, thereby adjustably fastening the member 12 to the lower end of the bar 6. The iron attaching member is further and more securely fastened to the 95 slotted lower end of the bar 6 by clamping bolts 15 which are arranged through said lower end of the bar at right angles to the slot 11 whereby when the nuts on said bolts are tightened up the slotted end of the bar 100 will be clamped into rigid engagement with the bolts 14 as will be readily understood.

The lower end of the iron attaching member 12 has formed thereon a right angular offset 16 and in the extremity of said offset 105 end of the member is a socket 17 which is adapted to be engaged with a stud 18 formed on and projecting upwardly from the top of the iron 19 near the pointed end thereof as shown. Also secured to the top of the 110 iron near the rear end thereof is a rearwardly projecting handle 20 which is pref-

erably constructed as herein shown and by means of which the iron is operated or guided over the ironing board.

In connection with my improved ironing device, I also provide an ironing board 21 which is hingedly connected at its inner end to the side wall of a room or to any other suitable support whereby when not in use the board may be folded up into close engagement with its support as clearly shown in dotted lines in Fig. 1 of the drawings. The board 21 is provided with a supporting leg 22 which is hingedly connected to the lower side of the board and is also adapted 15 to fold down to an out of the way position when the board is not in use and folded against its support in the manner described. Any suitable form of catch 23 may be provided for holding the board in a folded position. The upper surface of the outer portion of the board 21 is preferably concaved as at 24 so that as the iron is moved back and forth and the pressure bar thus swung out of a perpendicular position, an equal pressure will be applied to the iron as will be readily understood.

By constructing and arranging my improved ironing device as herein shown and described it will be seen that when the member 12 on the lower end of the pressure bar is engaged with the iron in the manner described that the pressure of the spring will be applied to the iron to hold the same in yielding engagement with the article being pressed and it will also be seen that by adjustably connecting the upper end of the member 12 with the lower end of the pressure bar that the pressure of the spring 1 on the iron may be controlled or regulated. By 35 means of my improved ironing device, articles may be ironed with the least possible amount of exertion on the part of the operator as all the pressure required is applied to

the iron by the spring 1 through the pressure bar 6 in the manner described and it is thus simply necessary for the operator to push and guide the iron over the article arranged on the ironing board.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

An ironing device comprising a double bowed spring, the upper member of which is adapted to be secured to a support, an attaching plate having its opposite ends secured to the outer face of the lower member of said spring, whereby the body of said plate is spaced from said spring, a pressure bar having a headed shank at one end swiveled in said attaching plate, the other end of said bar having a longitudinal slot at its free end, an iron engaging member having attaching bolts therein adapted to be slidably and adjustably engaged with the slot in said bar for adjustably securing said member to said bar, and clamping elements extending through said slotted bar end at right angles to the slot for forcing the side walls of the slot into rigid engagement with said attaching bolts.

In testimony whereof I have hereunto set my hand in presence of two subscribing witnesses.

DUNCAN J. FEELY.
